CAN FILLING MACHINE

Robert D. Rapp, Hammond, Ind.

Application September 2, 1933, Serial No. 688,015

5 Claims. (Cl. 226—95)

This invention relates to devices for filling containers, and more particularly to such devices for automatically filling cans or other containers with a powder or comminuted solid.

5 While cans and other containers have been automatically filled heretofore, certain disadvantages reside in the devices that have been used. In general, such prior apparatus have been of a bulky and cumbersome nature and unsatisfactory in operation. Difficulty has been experienced 10 with such devices in securing uniform and thorough filling of the containers. Also there has been a tendency for the material to clog or block certain passages in prior machines. And furthermore, in previous machines a large amount of material is wasted or lost in the can-filling operation.

To overcome the above, and other disadvantages in prior structures is one of the objects of 20 my invention.

Another object of my invention is to provide a device for filling cans that is of simple, yet sturdy construction.

A further object of my invention is to provide a 25 can-filling machine in which uniformity is obtained among the contents of each can.

And a still further object of my invention is to provide a device of which the operation may be terminated at any time without loss or waste of 30 the filling material.

To accomplish the above, and other important objects, my invention in general resides in the several elements and combinations thereof which will be hereinafter recited, it being understood, 35 of course, that various modifications may be made in either the individual elements or their combinations without departing from the scope of my invention.

To insure a complete understanding of my invention, reference is made to the accompanying 40 drawings which depict one specific embodiment of my invention, in which corresponding numerals refer to the same parts.

Figure 1 is a side elevation of one form of device 45 embraced in my invention;

Figure 2 is a top plan view of the apparatus shown in Figure 1;

Figure 3 is a cross-sectional view along the line 3—3 of Figure 1;

50 Figure 4 is an end view of the device shown in Figure 1, of what might be termed the entrance end;

Figure 5 is a detailed view of a can and its conveying mechanism;

55 Figure 6 is a view at the exit end of the device, showing means for removing excess contents from the can;

Figure 7 is a more detailed view in perspective 60 of the wiping element shown in Figure 6;

Figure 8 is a longitudinal sectional view of a preferred form of clutch;

Figure 9 is a plan view of the clutch as seen from the line 9—9 of Figure 8;

Figure 10 is a sectional view along the line 5 10—10 of Figure 8;

Figure 11 is a sectional view along the line 11—11 of Figure 8.

Referring more specifically to Figures 1 and 2, it will be noted that a standard 1 is provided upon 10 which a housing 2 of my invention is suitably mounted. The housing 2 terminates in a converging lower portion 3, which in turn is provided with a substantially circular trough 4 extending the length of the housing.

A top 5 is provided for the housing from which is suitably suspended a tapering bin 6. The bin 6 is divided into three compartments running lengthwise thereof, as indicated by dotted lines 7 of Figure 1. It will be observed that the bin compartments are tapered downwardly, as shown in Fig. 3, and are provided at their lower extremities with a mouth member 8 which runs the length of each compartment. It will be observed that the mouth member 8 is provided with flaring lips 9 25 in order to partially confine the stream of material emitted from the member 8.

The housing is provided with end members 11 which, of course, serve as walls for the two end compartments of the bin. A series of openings 12 is provided in the top 5, and these openings serve as inlets for supplying the chambers of the bin with the material to be supplied to the cans. The inlets may either be connected with a primary supply source by means of a pipe, as 35 shown by the dotted lines in Fig. 3, or the bins may be filled manually. As will be seen in Fig. 1, the middle bin is considerably larger than the two end bins, and two openings 12 are provided for such middle bin in order to secure even distribution of the material in such bin. It will, of course, be appreciated that the number of bins may be varied if desired.

Each bin is provided with a valve 13 which extends the length of the mouth member 8, and is 45 adapted to be seated therein. Valve stems 14 extend from the valve and project through suitable glands 15 in the top 5. As shown in Fig. 1, the valve 13 of each compartment is preferably provided with two such stems. Brackets 16 are 50 mounted on the top 5 and carry a guide 17 through which the stem 14 reciprocates. The guide 17 and gland 15 serve to maintain the stem 14 aligned. An arm 18 is suitably secured 55 to the stem 14.

A shaft 19 is mounted on the top 5 and extends the length thereof, being supported by suitable bearings 21 along its length. Adjacent each of the stems 14 eccentrics 22 are keyed on the shaft 19 provided with suitable eccentric sleeves 60

23. A threaded shaft 24 is mounted on each eccentric sleeve 23, and extends through an aperture in arm 18. A nut 25 is threaded on the shaft 24 at a point where it is adapted to bear against the underside of arm 18 upon rotation of the eccentric 22. Another nut 26 is adapted to be threaded on shaft 24 above the arm, and there is interposed between the nut 26 and arm 18 a helical spring 27.

10 It will, therefore, be observed that upon rotation of eccentric 22, the shaft 24 is reciprocated vertically, and when the nut 25 is suitably positioned, upward movement of the shaft 24 results in a raising of the arm 18. This in turn 15 raises the valve stem 14 to unseat valve member 13. Upon further rotation of eccentric 22, and the consequent downward movement of shaft 24, the valve stem 14 is permitted to fall, and also the spring 27 resiliently urges the stem 14 20 and valve 13 toward a seated position. It will, of course, be appreciated that the degree to which the valve is opened can be controlled by regulation of the nut 25. In other words, if the nut 25 is displaced downwardly from the position shown in Fig. 3, the valve will be opened only during the highest part of the eccentric's throw. Also, it will be observed that the tension of spring 27 can be varied by regulation of the nut 25.

25 The reciprocation of valve 13 serves to prevent clogging of mouth 8 and adhesion of the powder to bin 6. This tendency to clog and adhere varies with the character of the powder and climatic conditions, and in some instances is quite pronounced. By providing an intermittent flow, instead of a continuous flow, this tendency is curtailed.

30 The shaft 19 is driven by a chain 28, or other suitable power transmission, from a take-off shaft 29. The shaft 29 is mounted in suitable bearings 31 which are supported by a platform 32 extending from the top 5. Splined to the shaft 29 is a driven-half 33 of a clutch which may be reciprocated longitudinally of the shaft. As best shown in Fig. 8, this member 33 is made up of two sections 34 and 35, which are held together by means of bolts 36 or other suitable means. The member 34 is provided with recesses in which are arranged helical springs 37, and the member 35 is provided with apertures adapted to register 35 with these recesses and to receive the shanks of pins 38. It will be observed that the springs 37 tend to urge and maintain the pins 38 in extended position, but at the same time permit these pins to be retracted so that they are flush with the face of member 35.

35 As shown most clearly in Fig. 9, the member 34 is also provided with a cam surface 39, for a purpose to be described later.

40 The pins 38 are adapted to project within slots 41 of a driving-half 42 of the clutch. Member 42, which is freely rotatable upon the shaft 29, is provided with a shoulder on which is formed a sprocket 43 adapted to receive a chain 44 which is connected to a source of power, not disclosed.

45 Block 45, which is clearly shown in Fig. 9, is provided with a surface which corresponds to the pitch of the cam 39, is mounted in a guide 46 and is adapted to reciprocate therein. The block 45 is operable by means of a sliding rod 47 provided with a suitable handle. The rod 47 is supported by guide members 48, which permit reciprocation of the rod.

50 As clearly seen in Fig. 8, the rod 47 is provided with an inclined shoulder which corresponds to the lower face of block 45. Consequently, as the

rod is moved to the right in Fig. 8, the block 45 is forced upwardly, where it is in a position to bear against the cam surface of member 39. Upon further rotation of driven member 34 the member will be forced to the left in Fig. 8. When this displacement has taken place to such an extent that the pins 38 are completely removed from the slots 41, the two members 34 and 42 will be completely disengaged.

55 A yoke 49 is pivoted to a supporting bracket 50 mounted on the platform 32. The forks of this yoke are adapted to bear against the rear face of member 34, while the lower end is engageable by a bolt 51, or other suitable protuberance, on the rod 47. It will, therefore, be seen that as the rod 47 is moved to the left, the bolt 51 abuts against the lower portion of yoke 49, and this in turn throws the member 34 into engagement with the member 42. As will be appreciated, the first contact with member 42 will be by the heads of pins 38, and such pins, of course, will be depressed within their recesses until member 42 has rotated to a point where the slots 41 register with the pins, at which time they will be extended into such slots. The clutch will then be in complete engagement.

60 The cam 39 should be so positioned upon the periphery of the driven-half 34 that the instant the clutch members 33 and 42 are disengaged, the valves 13 in the bins will be in a closed position. It should be stated that I have found that the work being performed by the various elements geared to the shaft 29 is sufficient to stop the rotation of shaft 29 the moment the clutch is disengaged. It will, therefore, be seen that my clutch, and particularly the cam 39 and block 45, insure that the operation of the valves 13 will be terminated when the valves are in seated position.

65 The shaft 19 is provided with a power-take-off device 52 which may be in the form of two intermeshing bevel gears, one of which is keyed to shaft 19 while the other is mounted on a shaft 53. At the opposite end of shaft 53, a sprocket 54 is provided which carries a chain 55. The chain 55 is connected to a sprocket mounted upon a shaft 56, journaled at one end of the filling machine, as best shown in Fig. 3. A sprocket 56 is keyed to the center of this shaft, and is adapted to mesh with a chain 57.

70 As best shown in Fig. 5, chain 57 is supported lengthwise of the machine by a metal strip 58. Rails 59 are located on each side of the chain 57, as shown in Fig. 3, and the cans 60 to be filled are supported by both the rails 59 and chain 57. I prefer that the rails 59 afford the principal support for the cans, and that the contact between the chain 57 and the cans be sufficient merely to insure a movement of the cans through the machine.

75 The extent to which the chain 57 supports the cans is determined by the position of the strip 58. The strip 58 and rails 59 are supported by cross-brackets 61 placed at intervals along the length of the machine, and the strip 58 is secured to such brackets by means of screws or bolts 62. Washers 63 may be interposed between the strip 58 and bracket 61, and the number of these washers determines the elevation of strip 58 with respect to the brackets and to the rails 59.

80 It will, therefore, be seen that the extent to which the chain 57 (which travels over strip 58) supports the cans can be regulated by means of the washers 63. Therefore, if it is desired that

30

75

the chain 57 support more of the weight of the cans, additional washers 63 may be placed between the strip 58 and brackets 61, or such additional washers may be necessary from time to time as the chain shows signs of wear.

I have found the use of the combined rails and chains of considerable benefit, because it insures a vibration or jarring of the cans 60 as they pass through the machine during a filling operation. This is of considerable importance, particularly when the material fed the cans is of a light and voluminous nature, for it provides a means of thoroughly shaking and packing the cans. The jarring or vibration is occasioned by the fact that the chain 57 actually moves through the machine at a faster rate than any individual can, but it does engage the cans sufficiently to insure their movement along track 59. The jarring is directly due to the fact that the chain alternately engages the can frictionally, and then the frictional grip is broken and the can stops. The intermittent stopping and starting serves to thoroughly pack the cans.

Although only a portion of the chain is shown in the drawings, it will be appreciated that it is of the endless type. As shown in Fig. 1, the chain 57 and rails 59 are shown as extending beyond the limits of the filling machine. For instance, one end of the chain and track may cooperate with a device for loading the cans upon the chain, while the other end may be connected to a closing machine.

Suitably journaled within the circular trough 4 is an endless screw 64 which, upon rotation in one direction, tends to urge any material within the trough toward one end. At this end, there is provided a chute 65 which empties into an elevator chamber 66. Within the elevator 66, there is an endless screw 67, and at the top of the elevator a chute 68 is provided which empties into one of the compartments of bin 6, preferably the first compartment.

The screws 64 and 67 are driven from the shaft 19. As shown in Fig. 4, a sprocket 69 is keyed upon the shaft, and this sprocket carries a chain 71. The top end of screw 67 is provided with a beveled gear 72, which meshes with a beveled gear 73 keyed on a shaft 74. A sprocket 75 is also keyed on the shaft 74 which engages the chain 71.

The lower end of screw 67 is also provided with a beveled gear 76 which meshes with a corresponding gear 77 mounted upon a shaft 78. The shaft 78 also carries a sprocket over which passes a chain 79 which is connected to a sprocket upon a shaft 81 which carries the screw 64.

It will, therefore, be seen that during a filling operation, a certain amount of the material will overflow the cans 60, but such overflow is directed to the trough 4, in which it is constantly moved toward the chute 65 by means of the endless screw 64. Such material passes through the chute 65 to the lower end of elevator 66, and is there raised by means of screw 67 to the chute 68. The material is discharged from the elevator through chute 68 and directed to one of the compartments of bin 6.

Although the amount of material which each can receives may be very closely regulated by means of the adjustable nuts 25 and also the speed at which the machine operates, I have found it desirable to provide additional means for insuring a uniformity in the contents of each can. Such means is operable upon completion of the filling operation and just prior to the final passage of the cans from the filling ma-

chine. The specific means is clearly shown in Figs. 6 and 7, where it will be observed that I provide a wiper 82, of generally semi-circular shape. This wiper is preferably composed of fabric or some other suitable flexible material. As shown best in Fig. 6, it is adapted to extend slightly within the top of each can and to remove a portion of the contents. Each can obviously would be relieved of a portion of its contents, and the remaining contents will be the same for each can.

The wiper 82 is mounted upon a shoe 83, which in turn is rigidly secured to a shaft 84. The shoe 83 and shaft 84 extend within a well 85, against one side of which the face of shoe 83 is adapted to lightly bear. This, of course, prevents rotation of shoe 83. The upper end of shaft 84 is threaded and receives a nut 86. The nut 86 is rotatively fitted within a well 87 on the top 5, and the upper end of such nut forms a beveled gear 88. A beveled gear 89 meshes with gear 88, and is keyed to a shaft 91 provided with a handle 92. It will be observed, therefore, that rotation of handle 92 effects a vertical displacement of the shoe and wiper 82. There is secured thereby a control of the amount of material that is removed from each container, which will depend upon the extent to which the wiper 82 projects into each can.

It is believed that from the foregoing the operation of my invention will be readily apparent. The compartments of bin 6 are first filled with the material to be fed the cans, or as heretofore stated, these bins may be continuously supplied with the material through means of the feed pipes such as shown in dotted lines of Fig. 3.

At the beginning of operations the power source to which the chain 44 is connected is started. Inasmuch as clutch members 34 and 42 are disengaged upon termination of a filling operation, rod 47 is pushed to the left. This forces yoke 49 against the driven-half 34, and at the same time block 45 is permitted to fall within guide 46 so that it is freed from engagement with cam 39. As driven-half 34 is urged toward the driving member 42, the pins 38 will be depressed until the slots 41 of the driven member register with the pins, at which time the springs 37 will force the pins into such slots. Further movement of driving member 42 effects seating of the pins against the rear end of the slot, which results in rotation of driven member 34 with the driving member 42.

This rotation of driven member 34 is transmitted through shaft 29 and chain 28 to the shaft 19. Inasmuch as the cans 60 have been placed upon the conveyor prior to the operation of the device, rotation of shaft 19 starts the cans on their passage through the apparatus, by reason of the take-off 52 and associated transmission elements.

Rotation of the shaft 19 also commences operation of the valves 13. The eccentrics 22, keyed upon shaft 19, raise the arms 18 during a part of the eccentric's rotation, and this results in a raising or unseating of valve 13. The weight of the valve 13 and its associated mechanism, as well as the resiliency of spring 27, serve to return the valve to a seated position upon further rotation of the eccentric. It will be observed, of course, that the springs 27 afford a cushioning effect during reciprocation of valve 13. The reciprocation of valve 13 provides an intermittent flow of the material through bin 6, and such

intermittent flow serves to prevent any clogging of mouth 8 or adhesion of the material to the bin.

Although the cans 68 are located at such a position below the mouth 8 of the bin as to receive practically all of the material discharged from mouth 8 into the can, there nevertheless is a certain amount of the material that is not received by the cans, and also, in some instances, the cans overflow. Furthermore, it is, of course, obvious that until the operation has proceeded long enough to have the cans throughout the entire length of the machine, some of the material will be discharging without any cans being below.

15 In any of such events, the material that is not directed into cans will fall to the trough 4. In view of the gearing between the screw 67 and shaft 19, and between screw 67 and screw 64, any such material in trough 4 will be urged toward chute 65 and passed through such chute to elevator 66. Screw 67 in elevator 66 hoists such material to chute 68, which returns the material to one of the bin compartments where it is re-fed through mouth 8 to the cans.

20 25 Just prior to the time that the cans leave the filling machine, a portion of their contents is brushed or scooped out by the wiper 82, so that the cans go to the closure machine with a uniform amount of material.

30 Also, it will be noted, that the cans are subjected to a slight jarring or vibration as they are being filled, resulting from the fact that they are partly supported by tracks 58 and partly by chain 57, the chain 57 having sufficient engagement with the can to effect its movement through the machine, but not sufficient to have such movement continuous and regular. As the chain is subjected to wear, and thereby becomes lowered with respect to rails 58, or in the event that it 35

40 is desirable that the chain 57 assume a greater portion of the weight of the cans and thereby reduce vibration of the cans, additional washers 63 may be inserted between strip 58 and bracket 61.

45 When it is desired to stop the operation, lever 47 is moved to the right in Fig. 8, thereby releasing pressure on yoke 48, and at the same time raising block 45 so that it engages cam 38, thereby forcing driven-half 34 out of engagement with the driving member 42 of the clutch. As stated, the moment that the pins 38 are free of the slots 41, shaft 29 ceases to rotate, and the exact position of rotation at which the pins 38 are freed of the slots is such that the valve 13 is seated, 50 and thereby any waste of material is prevented.

55 It will be observed that I have provided a can filling machine of simple construction and easy operation. Its efficiency is due to the fact that the cans are uniformly filled because of the vibration of the cans during the passage through the machine, and in view of the fact that wiper 82 removes all material in excess of that which may be desired. The clutch arrangement insures that no material will be discharged upon 60 termination of the filling operation, and the return trough 4 and elevator 66 prevent any loss of material from the circuit. The reciprocating valves 13 provide an intermittent flow through the bin 6, which serves to prevent material adhering to the bin or clogging the discharge mouth 8. Adjustability of these valves may be secured by means of nuts 25 and 26.

65 While my invention is particularly adapted for use with powders or other finely comminuted solids, it will, of course, be appreciated that it is

not limited thereto. It will be understood that the word "can" appearing in the claims is not to be limitatively construed but is to include all types of containers, and also the word "overflow" includes material that never reaches the can, as well as such material that actually overflows from the cans.

70 While I have shown in the accompanying drawings and described in the specification the preferred embodiment of my invention, I wish it to be distinctly understood that I am not limited to the specific structure there described, but that my invention is to be determined solely by the scope of the appended claims.

I claim:—

15 1. A can filling apparatus comprising a chamber for containing material to be fed to the cans, an outlet from said chamber, a valve adapted to continuously reciprocate vertically in said outlet while a can is therebelow, means for conveying the cans at a substantially uniform rate below the outlet, means for catching an overflow of the material, means for conveying the overflow to a vertical member provided with a screw which is adapted to return the overflow to the chamber, and means for removing from the cans an excess of contents.

20 2. In a can filling apparatus in which the cans are adapted to travel on a conveyor while being filled, a continuous chain adapted to partially bear the weight of the cans, a track in combination with the chain and adapted to partially bear the weight of the cans, a strip adapted to support the chain throughout the path of movement of the cans thereon, brackets for supporting the track and strip and means adapted to be inserted between said strip and brackets for varying the relative heights of the strip and track.

25 3. In a can filling apparatus, means to contain a supply of relatively powdered material to be fed to the cans, a discharge outlet therefrom, a vertically reciprocable valve adapted to intermittently open and close the outlet while a can is therebelow, actuating means for the valve, a clutch in association with the valve actuating means, and cam means for disengaging the clutch when the valve is in closed position.

30 4. A can filling apparatus comprising a partitioned chamber adapted to hold the material to be fed to the chamber, an outlet at the base of each compartment and extending the length thereof, a valve for each outlet, a stem for each valve, an eccentric and strap therefor cooperating with each valve stem, said eccentrics being mounted upon a common shaft, means to receive an overflow from the cans and direct the same toward one end of the apparatus, means to elevate the overflow and return it to the chamber, means for vibrantly passing the cans through the apparatus and beneath the compartment outlets, common means for actuating the eccentric shaft, the elevating means and the conveying means, and means to insure closure of the valves upon termination of the operation of the device.

35 5. In a can filling apparatus, means to contain a supply of relatively powdered material to be fed to the cans, a discharge outlet therefrom, a reciprocable valve adapted to open and close the outlet while a can is therebelow, actuating means for the valve, a clutch in association with the valve actuating means, and means for disengaging the clutch when the valve is in the closed position.
